CLAIM

The ornamental design for a container as shown and described.

DESCRIPTION

FIG. 1 is a top perspective view of my new design for a container with an environmental lid and straw.

FIG. 2 is a top perspective view thereof shown with the environmental lid and straw removed for clarity of disclosure;

FIG. 3 is a bottom perspective view of the container of FIG. 2;

FIG. 4 is a front view thereof;

FIG. 5 is a back view thereof;

FIG. 6 is a right side view thereof;

FIG. 7 is a left side view thereof; and,

FIG. 8 is a top view thereof.

The broken lines in FIG. 1 depict environment and form not part of the claimed design.

1 Claim, 8 Drawing Sheets
